UNITED STATES PATENT OFFICE.

FRED STEINBRENNER AND CHARLES SLEMENDA, OF PITTSBURGH, PENNSYLVANIA.

RAIL-JOINT.

1,083,036.

Specification of Letters Patent.

Patented Dec. 30, 1913.

Application filed August 5, 1913. Serial No. 783,200.

To all whom it may concern:

Be it known that we, FRED STEINBRENNER and CHARLES SLEMENDA, citizens of the United States of America, residing at Pittsburgh, in the county of Allegheny and State of Pennsylvania, have invented certain new and useful Improvements in Rail-Joints, of which the following is a specification, reference being had therein to the accompanying drawing.

This invention relates to rail joints, especially designed for connecting the confronting or abutting ends of rails used in connection with street railways.

15 The primary object of our invention is to provide novel splice bars that form a chair for safely supporting the confronting or abutting ends of rails, whereby the rails cannot become vertically or laterally displaced.

20 A further object of our invention is to provide a simple and durable and inexpensive rail joint that can be easily and quickly installed, the joint having novel braces that afford sufficient bearing for the rail joint upon ties or other supports in order to withstand the great weight of rolling stock.

We attain the above and other objects by a mechanical construction, that will be hereinafter specifically described and then claimed.

Reference will now be had to the drawing, wherein:—Figure 1 is a side elevation of the rail joint, Figs. 2 and 3 are perspective views of splice bars constituting the joint, and Fig. 4 is a cross sectional view of the rail joint.

25 A rail joint in accordance with this invention comprises a tie plate 1 and formed integral with said tie plate is a longitudinal outer splice bar 2. The splice bar 2, adjacent to the ends thereof, is provided with braces 3 and the outer ends of said braces have openings 4 for spikes or other fastening means 30 employed for securing the rail joint to ties or other supports.

35 The splice bar 2 and the braces 3 are adapted to brace and hold the outer sides of rails 5 arranged upon the tie plate 1 and the upper edge of the splice bar 2 engages 40 under the threads 6 of said rails.

The edge of the tie plate 1 has an offset portion 7 provided with an opening 8, the purpose of which will presently appear.

The inner sides of the rails 5 are held and 55 braced by an inner splice bar 9 having lateral flanges 10 and 11 connected by braces 12 similar to the braces 3. The lateral flange 10 extends under the tread flanges 13 of the rails 5 and the lateral flange 11 rests upon 60 the inner base flanges of the rails 5, also upon the offset portion 7 of the tie plate 1. The flange 11, intermediate the ends thereof, has a notch 14 adapted to register with the opening 8 and a wedge or key 15 extends 65 through said notch into the opening 8, whereby the splice bar 9 can be locked relatively to the splice bar 2. A screw 16 or other fastening means can extend through the key 15 into an opening 17 provided 70 therefor in the wall of the notch 14.

It is thought that the utility and the manner of assembling the rail joint will be apparent without further description and while in the drawing there is illustrated a 75 preferred embodiment of the invention it is to be understood that the structural elements are susceptible of such variations and modifications as fall within the scope of the appended claim.

80 What we claim is:—

In a rail joint, the combination with street rails, of a tie plate adapted to support the base flanges of said rails, an outer splice bar formed integral with said plate for bracing 85 the outer sides and treads of said rails, braces carried by said outer splice bar adjacent to the ends thereof and affording means for securing said tie plate to ties, an inner splice bar engaging the inner sides of said 90 rails, lateral flanges carried by said inner splice bar with one of said flanges bracing the tread flanges of said rails, braces connecting said flanges adjacent to the ends of said inner splice bar, an offset portion carried by said tie plate, a key adapted to engage said inner splice bar and extend through the offset portion of said tie plate, and means engaging in said inner splice bar for retaining said key in adjusted position. 100

In testimony whereof we affix our signatures in the presence of two witnesses.

FRED STEINBRENNER.
CHARLES SLEMENDA.
